CLAIM

The ornamental design for a shirt, as shown and described.

DESCRIPTION

FIG. 1 is a front elevational view of a shirt showing my new design;

FIG. 2 is a rear elevational view thereof;

FIG. 3 is a right side elevational view thereof;

FIG. 4 is a top plan view thereof;

FIG. 5 is a bottom plan view thereof; and,

FIG. 6 is a perspective view thereof.

The broken lines shown in FIGS. 1-6 represent stitching.
